UNITED STATES PATENT OFFICE

JOHN H. GREER, OF SAN FRANCISCO, CALIFORNIA, ASSIGNOR TO BANKERS UTILITIES CO., OF SAN FRANCISCO, CALIFORNIA, A CORPORATION OF CALIFORNIA

BANK

Application filed December 4, 1929. Serial No. 411,515.

My invention relates to banks or safes for receiving and retaining money, such as coins, and particularly to banks adapted to be carried by the user presenting the appearance of a book. The book-like binding may be embossed or otherwise treated to present advertising matter or other indicia. These book form banks are popularly employed as advertising novelties by commercial and savings banks.

An object of my invention is to provide a book form bank having means for receiving and retaining coins.

A further object of my invention is to provide a book form bank which is of simple and economical construction and which can be made of such size as to be conveniently carried in a pocket of the clothes of the owner.

The foregoing objects of my invention together with some of its advantageous features are set forth in the following description wherein I shall outline the preferred embodiment thereof. My bank is not to be limited to the form shown in the drawings and described herein as the invention, as defined in the appended claims, may be embodied in a plurality of forms.

Figure 1 is a plan of an embodiment of my invention illustrating the cover in open position.

Figure 2 is a section taken on the line 2—2 of Fig. 1.

Figure 3 is a section taken on the line 3—3 of Fig. 1.

Figure 4 is a detail of one of the coin retainer pockets.

Figure 5 is a cross section taken on the line 5—5 of Figure 4.

Figure 6 is another detail of a coin retainer pocket showing the depressions which are made in the top sheet when a coin is extracted from the pocket.

Figure 7 is a cross section taken on the line 7—7 of Figure 6.

In its preferred form, the bank of my invention comprises a cover adapted to be folded to present the appearance of a book, together with a plurality of apertured sheets which are suitably attached to each other,

such as by an adhesive, and secured as a whole to the cover.

As disclosed in Figure 1 of the drawings, the book form bank of my invention preferably includes a covering usually fabricated of paper, leather or other flexible material. The cover is centrally folded to provide a back 2 and a front 3.

Means for receiving and retaining coins are provided and usually include a plurality of superimposed apertured sheets 4 and 5 which are conveniently secured to one another, such as by an adhesive, and secured as a whole to the back cover of the bank. A sheet 4 is disposed adjacent the cover of the bank and is preferably provided with a plurality of apertures 6 substantially circular in general contour but having an extended oval portion 7. Another sheet 5 is superimposed upon and secured to sheet 4 and is preferably provided with a plurality of apertures 8 of semicircular general configuration having notches 9 disposed over the oval portions 7 of apertures 6. Apertures 8 register with apertures 6 leaving walls 11 extending above the apertures 6 to provide coin retaining pockets 12. Coins are retained in the pocket 12 with the oval portions 7 of the apertures 6 extending above the top of the coins.

In order to assist in the extraction of coins from the pocket, I preferably make the apertures 8 smaller than the apertures 6 thus forming lips 13 which extend above the oval portions 7 of apertures 6. Since I preferably make the upper edge of walls 11 of substantially the same width as the diameter of the coins which are inserted in the pockets, it is necessary to exert force to extract the coins. A tool or a finger of the hand may be inserted adjacent the lips 13 depressing them to secure a hold upon the top of the coin and, in this manner, the coin may be grasped and pulled from the pocket.

My bank may be formed to retain one or more coins in each pocket, as desired. If only one coin is inserted and retained in a pocket it is only necessary to have the two sheets 4 and 5 suitably secured to each other, such as by an adhesive, to form the pockets. If it is desired to retain two or more coins

in each pocket, a thicker sheet or several sheets, having apertures similar to sheets 4 and 5 can be superimposed upon and secured to one another and thus pockets of any convenient depth are formed.

5 My bank can be conveniently constructed so as to receive and retain coins of different diameters, by merely enlarging the apertures in the sheets. Further, it is to be noted that 10 the apertures in each sheet may not be all of the same size as it may be desired to retain coins of different value and hence of different sizes in the one bank.

15 The front cover 3 can be folded over the sheets serving as a closure and also serving to conceal the coins which are retained in the pocket. This cover has the additional function of preventing the pockets of the bank from catching articles in the clothing.

20 I claim:

1. In a book form bank, a covering of flexible material adapted to be folded to present the appearance of a book, a flexible sheet having a substantially circular aperture 25 therein secured to said covering, and a second flexible sheet adhesively secured to and superimposed upon said first named sheet, said second sheet having a substantially semi-circular aperture therein adapted to register 30 with said first named aperture.

2. In a book form bank, a covering of flexible material adapted to be folded to present the appearance of a book, a sheet having a substantially circular aperture therein secured to said covering; said aperture having a portion of oval contour, and a second sheet 35 secured to and superimposed upon said first named sheet; said second sheet having a substantially semi-circular aperture with a 40 notched portion therein adapted to register with said first named aperture.

3. A book form bank comprising a covering adapted to be folded upon itself, a first sheet having an aperture therein on said 45 covering, and a second sheet on said first sheet; said second sheet having an aperture therein of substantially one-half the size of the aperture in said first sheet and adapted to register therewith, said covering, sheets 50 and apertures cooperating to form a pocket for the reception of a coin and said second sheet being adapted to be depressed adjacent the aperture therein whereby said coin can be extracted from said pocket.

55 In testimony whereof, I have hereunto set my hand.

JOHN H. GREER.
